CASE B.

To all whom it may concern:

Be it known that I, EMIL CRISAND, of New Haven, in the county of New Haven and State of Connecticut, have invented a new Design for Embroidery-Pattern; and I do hereby declare the following, when taken in connection with the accompanying drawings and the letters of reference marked thereon, to be a full, clear, and exact description of the same, and which said drawings constitute part of this specification, and represent the design.

This invention relates to a design for embroidery-pattern, intended especially for perforated board; and it consists in the peculiar configuration and ornamentation of the motto, as shown in the accompanying illustration.

The motto which constitutes the principal feature in this design is "The Lord will Provide."

The letters which compose this motto are of the form shown in the accompanying illustration, the capitals being the principal features in this part of the design. Interwoven with the several letters is a tracery of vine-work, also clearly shown in the accompanying illustration.

I claim—

The design for embroidery-pattern herein described, consisting of the motto "The Lord will Provide," in form and ornamentation as shown in the accompanying illustration.

Witnesses: EMIL CRISAND.
